UNITED STATES PATENT OFFICE.

JOHN P. WILLIAMS, OF BUFFALO, NEW YORK, ASSIGNOR TO PRATT & LETCHWORTH CO., OF BUFFALO, NEW YORK, A CORPORATION OF OHIO.

COMBINED STOP LUG AND CENTER FILLER CASTING.

Application filed September 22, 1926. Serial No. 136,946.

This invention relates to combined stop lug and center filler castings.

An object of the invention is to provide a combined back stop and center casting which has striking faces adapted to co-operate with a draft gear having the usual yoke, and which casting has an integral perforated center pin section, together with a transverse front wall against which the striking faces of the casting are braced, transverse diaphragms connecting the bottom and side walls and center pin section of the casting, and a longitudinally extending diaphragm which connects the front and rear walls of the casting, intersects certain of the transverse diaphragms, and is connected to the center pin section, providing a simple construction of great strength and compactness.

Other and further objects of the invention will more clearly appear from the description and claims hereinafter following.

In the drawings, forming part of this specification, Figure 1 is a top plan view of a combined stop and center casting constructed in accordance with my invention, and showing the same applied to the center sill plates of a railway car, portions of the usual shock absorbing mechanism being shown in dotted lines. Figure 2 is a central vertical longitudinal sectional view through the center casting, and showing said casting detached from the center sill plates. Figure 3 is a transverse vertical sectional view taken substantially on the line 3-3 of Figure 1. And Figure 4 is a transverse vertical sectional view of the invention corresponding substantially to the line 4-4 of Figure 2.

As shown in the drawing, the numerals 5-5 represent spaced center sill plates of usual construction having angle members 6-6 secured to the lower outer edges thereof, and having oppositely arranged angle members 7-7 disposed along the inner lower edges of the center sill plates 5-5.

The combined back stop and center filler casting is adapted to be arranged between the center sill plates 5-5 as shown, and said casting includes side walls 8-8 which are off-set at the lower portions as indicated at 9 to accommodate the vertical flanges of the angle bars 7-7 secured to the inner lower faces of the center sill plates. The casting also includes a bottom wall 10 which con-

ncts the side walls 8-8 and rests upon the horizontally extending flanges of the angle member 7-7. The bottom wall 10 is cut out at its forward portion as indicated at 11 to provide clearance for the end of the draft yoke shown in dotted lines in Figure 1, the portion of the bottom wall at each side of the cut-out being integrally connected with the oppositely extending inturned flanges 12-12 formed upon the forward ends of the side walls 8-8, said flanges being arranged to provide stops for the rear end of the shock absorbing mechanism as shown in dotted lines in Figure 1.

The flanges 12-12 are braced by means of a top rib 13 which extends from each of the flanges in an inclined direction toward the adjacent side wall. Additional bracing ribs indicated at 14 are provided which extend from each flange 12 inwardly where they merge into a forward transversely extending diaphragm or wall 15, said wall being formed integrally with the bottom wall 10 of the casting a slight distance in the rear of the cut out portion 11 and having its ends connected to the side walls.

At the opposite end of the casting there is provided a rear wall or diaphragm 16 of somewhat restricted height which connects the side walls 8-8, and bottom wall 10 of the casting, as best shown in Figure 2, portions 17-17 of the side walls 8-8 at the rear of the casting extending somewhat beyond the diaphragm or end wall 16, the portions 17, as well as the remaining portions of the side walls 8-8 being provided with a plurality of rivet holes indicated at 18, adapted for the reception of rivets 19, which are utilized for securing the casting in position between the center plates.

Intermediate the front and rear walls or diaphragms 15 and 16 is provided an intermediate transverse diaphragm 20 formed integrally with the side walls 8-8, the top edge portions of the diaphragm being inclined toward the bottom wall 10, and at the center the diaphragm 20 is formed integrally with an annular center pin section 21 in which is formed the king pin opening 22, the open 22 extending downwardly through the bottom wall 10 as best shown in Figures 2 and 4, the bottom wall at a point adjacent the center pin section being depressed as indicated at 23. At opposite sides of the central king pin section are disposed trans-

versely extending diaphragms 24 and 25 which connect the side walls 8-8 of the casting and the bottom 10 thereof, said diaphragms being spaced longitudinally of the casting from the diaphragm 20 a suitable distance as shown, said diaphragms each having its top edges inclined toward the center in the direction of the bottom wall 10. A longitudinally extending centrally disposed diaphragm is provided which is connected at its forward portion with the wall 15 and at this point is of a height corresponding thereto, the diaphragm 26 extending rearwardly and gradually diminishing in height, until the same intersects the diaphragm 24 and thence merges into the annular wall forming the center section 21. The diaphragm 26 is interrupted by the center pin section, but on the opposite side of said section is connected integrally therewith as shown at 27 and thence intersects the diaphragm 25 and merges with the end wall 16, the height of the diaphragm gradually diminishing to correspond to the height of the diaphragm 25 and end wall 16 at their central portions.

By reference to the preceding description taken in connection with the drawings, the purpose and use of the casting will be clearly understood, the braced flanges at the forward portions of the casting providing abutments for the rear of the shock absorbing mechanism, while the cut out portion 11 permits the necessary movement of the yoke. The center pin section is adapted for the reception of the usual center pin, and by the use of the transversely arranged diaphragms connecting the bottom wall, side walls and center pin section, together with the longitudinally extending diaphragm connecting the end and bottom walls of the casting, intersecting some of the transversely extending diaphragms, and connected to the center pin section, a casting is provided which is braced in all directions in a simple and effective manner.

While I have herein shown and described what I consider the preferred manner in carrying out the invention, the same is merely illustrative, and I contemplate all changes and modifications which come within the scope of all the claims appended hereto.

I claim:

1. A combined center filler and stop lug casting comprising longitudinally arranged spaced side walls adapted to be secured to the center sills of a railway car, an integrally transversely extending horizontal bottom wall having a central cut-out section at its forward portion to permit movement of

a draft yoke, transversely extending integral walls at the forward and rear portions of said casting, said front wall being disposed in the rear of said cut-out section and formed integrally with said side and bottom wall, and the rear wall merging with said side and bottom walls, a center pin section, formed integrally with said bottom wall and a transversely extending diaphragm connecting said central section with said side walls, a diaphragm at each side of said center section, said diaphragms connecting said side walls and said bottom wall, a longitudinally extending centrally disposed diaphragm connected with said front and rear wall and with said center pin section, and intersecting the remaining diaphragms, being formed integrally therewith, and inturned flanges at the forward portions of said side walls to provide stop lugs, said flanges being braced by means of horizontally disposed ribs extending between said flanges and the forward wall of said casting.

2. A combined center filler and stop casting, comprising side walls, a bottom, and spaced end walls connecting said sides and bottom; spaced stop members braced against said side walls and the adjacent end wall; a plurality of transversely extending diaphragms intermediate said end walls and connecting the side walls and bottom wall of said filler, a center pin section connected to said bottom wall and connected to said side walls by one of said transverse diaphragms, and centrally disposed longitudinally extending means connecting said end walls with said center section, and intersecting the remaining diaphragms.

3. A combined center filler and stop casting, comprising side walls, a bottom, and spaced end walls connecting said sides and bottom; spaced stop members braced against said side walls and the adjacent end wall; a plurality of transversely extending diaphragms intermediate said end walls and connecting the side walls and bottom wall of said filler, a center pin section connected to said bottom wall and connected to said side walls by one of said transverse diaphragms, and centrally disposed longitudinally extending means connecting said end walls with said center section, and intersecting the remaining diaphragms, said center pin section being depressed with reference to the side and an end wall, and said diaphragms being inclined toward said center section.

In witness that I claim the foregoing I have hereunto subscribed my name this 15th day of September, 1926.

JOHN P. WILLIAMS.
